UNITED STATES PATENT OFFICE.

ROBERT J. OWEN AND HARRY D. RINDSBERG, OF CINCINNATI, OHIO, ASSIGNEES TO
HARRY J. HATER, OF CINCINNATI, OHIO.

MOLD.

Application filed November 14, 1923. Serial No. 674,359.

To all whom it may concern:

Be it known that I, ROBERT J. OWEN, and I, HARRY D. RINDSBERG, citizens of the United States of America, residing at Cincinnati, in the county of Hamilton and State of Ohio, have invented certain new and useful Improvements in Molds, of which the following is a specification.

This invention relates to permanent metal molds of the kind used in making castings from metals and metallic alloys such as aluminum and its alloys which have comparatively low fusing points. More particularly, the invention relates to molds of this type for producing hollow or cup-shaped cylindrical castings such as skirted pistons for internal combustion engines.

Specifically the present invention relates to certain definite improvements in the molding device shown and described in application Serial No. 630,600, filed April 7, 1923, by John L. Schnobrich.

In the device disclosed in said application, as well as in the prior art, there are provided a pair of separable mold sections which are slidably mounted upon a suitable base, each section having a complementary part of the mold cavity, and the base itself forming the bottom of such mold cavity. The present invention seeks to improve upon the former construction by providing each movable section with a portion, which portions, when the sections are assembled, together constitute the bottom of the mold cavity, and by mounting the movable sections upon spaced guide rails in such a manner that the lower portions thereof, forming the bottom of the mold cavity, are supported above the base or frame of the machine.

The present invention also contemplates provision of an improved construction of supporting rack for receiving the core sections when they are removed from the mold cavity.

In order that the invention may be readily understood, reference is had to the accompanying drawings forming part of this specification, and in which:

Figure 1 is a plan view of the improved molding machine;

Figure 2 is a longitudinal vertical section therethrough on the line 2--2 of Figure 1;

Figure 3 is a transverse section substan-

tially on the line 3--3 of Figure 1 looking in the direction of the arrows, and

Figure 4 is a fragmentary side elevation showing one of the supporting rails with the mold sections resting thereon.

We have selected for purposes of illustration, a "one-man mold" of the type shown in the above mentioned application, although the present invention is by no means limited to a mold of this special type.

Referring to the drawings in detail, our improved molding machine comprises a suitable base or frame 1 preferably of skeleton construction, and comprising the cross-bars 1^a. On this frame, in a manner to be hereinafter described, are mounted two separable mold sections 2 and 3. The meeting faces of these sections are so shaped as to form within the same a mold cavity 4, which, in the case of a piston mold, is of course circular in plan.

A gate or inlet, leading to the mold cavity 4, is also formed in the meeting faces of the two mold sections, as indicated at 5 in Figure 3, and this gate may be of any desired construction.

It is common practice in apparatus of this character to provide seven cooperating core members fitting within the upper part of the mold cavity, and we have illustrated these seven members in the drawing. It will be understood however that any suitable or desired number or construction of core members may be employed in connection with the present invention.

The core members are clearly shown in Figures 1 and 2 and comprise a central member 7, flanked by a pair of associated members 6 and 8, and four members 10, 11, 12 and 13 fitting in pairs at each side of the central group.

As illustrated, the three middle members 6, 7 and 8 are provided with upstanding rods or handles 9 by which they may be manipulated, and an arm, having a handle at its end, is also rigidly secured to each of the four core members 10, 11, 12 and 13, such arms extending in the same general direction and being substantially horizontal. The arms are designated by the characters 14, 15, 18 and 19, the arms 14 and 15 being bent around through substantially 180 degrees, and the four handles carried by the arms are designated 16, 17, 20 and 21, respectively.

In order to properly position the core members 10 and 11, and 12 and 13, we preferably provide pins 22 and 23, set into the mold sections 2 and 3, respectively, adjacent the meeting edges of the core members, as clearly shown in Figures 1 and 2.

Set into opposite sides of the mold sections 2 and 3 are two pairs of pins or studs 24. The studs forming each pair are parallel and spaced slightly apart, and their outer ends are reduced and threaded as shown at 25. A plate or bracket 26, having a slot 27 therein, fits over the ends 25 of each pair of studs 24, and is secured in position thereon by means of nuts 25^a.

The lower ends of the plates or brackets 26 are forked, as indicated at 28 in Figure 2, and these forked ends are so shaped as to snugly fit over racks 29, circular in cross-section, and provided with teeth on their upper sides. To the inner end of each rack is secured a core member 30, such member forming in effect a continuation of the rack body and being in alinement therewith. These core members 30 slide freely through the side walls of the mold sections 2 and 3, and the outer ends of the racks 29 are slidably mounted in brackets 32 secured to the ends of the base or frame 1 by means of bolts 33.

Instead of the bottom of the mold cavity being formed by the base itself, as in the prior application above mentioned, such bottom is formed, in our improved construction, by means of a pair of plates 34 and 35 secured to the lower ends of the mold sections 2 and 3, respectively, as by screws 36. These plates cooperate with the mold sections proper to completely enclose the mold cavity, entirely independent of the base of the machine.

Interposed between the end of each rack 29 and the adjacent wall of the mold section, and surrounding and rigidly secured to the core member 30 is a collar 31. This collar is of such a size that it cannot pass through the forked ends of the bracket 26, but will engage with the prongs 28 thereof for a purpose hereinafter described.

One of the racks 29 is in engagement with a pinion 37 secured to a shaft 38 journaled in extensions 32^a of the bracket 32 and extending a considerable distance beyond said bracket, as indicated at 38^a in Figure 1, this extended portion being preferably enlarged. At the extreme end, this enlarged portion 38^a of the shaft 38 carries an operating lever 39, having an arm 40 pivotally connected at 41 with a link 42. The other end of this link is itself pivotally connected at 43 with a crank arm 44 secured to a shaft 45, journaled in extensions 32^a of the bracket 32 at the other side of the mold, and having rigidly mounted thereon a pinion 46 which engages with the other rack 29.

Instead of the mold section resting upon the base of the machine, as in the prior art, we provide in the present improved construction, spaced rails or runways 47 on which the sections are slidably mounted. By reference to Figure 3 it will be seen that these rails are disposed one at each side of the frame and are so positioned relative to the plates 34 and 35 that these plates lie between, but out of contact with the supporting rails. Each rail 47 is provided along its outer edge with an upstanding guide flange 48, the mold sections fitting snugly between such guide flanges, as shown in Figure 3.

Adjacent the meeting edges of the mold section each guide flange 48 is cut away down to the level of the bearing surface of the rail, as indicated at 48^a in Figure 4. The purpose of this is to permit the ready removal or brushing away of any foreign matter that may lodge upon the runways or rails and which is pushed toward the center when the mold sections are brought together. If it were not for this cut away portion it would be difficult, if not impossible, to clean away the foreign matter from behind the guide flange as the mold sections move toward each other.

From the foregoing it will be obvious that when the lever 39 is swung upwardly from the position shown in Figure 2, the two pinions 37 and 46 will be simultaneously rotated, and will simultaneously cause the racks 29 to travel in opposite direction. The first part of this movement results in withdrawing the core members 30 from the cavity of the mold. After this initial movement, a further movement in the same direction causes the collars 31 to engage the lower forked ends of the brackets 32, and thus, as the movement of the racks continues, these brackets, together with the mold sections 2 and 3, to which they are attached, are simultaneously moved away from each other or in opposite directions, such sections sliding upon the runways 47 as they are moved.

In order to lock the mold sections tightly together during the casting operation, we provide, as has already been proposed, a pair of latches or hooks 49, mounted one at each side of the mold. These hooks are adapted to engage pins 50, set into one of the mold sections, and are so formed that the point or beak of the hook underlies the pin, when in locked position, as shown in dotted lines in Figure 2. In order therefore to disengage the hooks from the pins it is necessary to first move them longitudinally so that the beak will clear the pins when the hooks are swung upwardly on their pivots. To accomplish this, we employ the construction described in detail in the above mentioned application and shown in Figures 1 and 2 of the present case.

From these it will be seen that each hook 49 is journaled upon an eccentric 51, these eccentrics being rigidly secured to a shaft 52 journaled in the mold section 3. The ends of the shaft 52 are extended beyond the eccentrics and carry transversely disposed radially projecting pins 56. These pins are adapted to engage pins 55, carried by the hooks 49, so as to elevate the hooks into release position as the shaft 52 is rotated. In order to rotate this shaft, we secure to one end thereof a crank arm 53 provided at its end with a handle 54, as clearly shown in Figure 1.

In order to facilitate the work of the single operator of this machine of the "one-man type", and to avoid possible damage to the core members, we provide a special holder to receive these core members when they are removed from the mold cavity. This holder comprises a pair of upstanding arms or side members 57 rigidly secured to the base plate or frame 1. To the upper ends of the side members 57 are rigidly secured a pair of inclined pans or trays 58 and 59, by means of brackets or lugs 58^a and 59^a, preferably formed integral therewith. Each of these pans or trays may conveniently be made of cast iron or the like, but are provided with a lining 60 of sheet brass or other relatively soft metal so as to prevent damage to the core members when the same are placed therein.

It will be understood that while we have shown and described our improved features of construction in connection with a mold of the "one-man type", our invention is by no means limited to molds of this type, but is equally applicable to the older types of mold for which two operators are required.

What we claim is:

1. In combination, a metal mold for forming cylindrical articles, comprising a pair of movable separable sections each having an inner surface forming part of the curved wall of the open top mold cavity, and a pair of independent plates secured one to the lower end of each of said sections and serving, when said sections are assembled to form the bottom of the mold cavity, and supporting means on which said sections are slidably mounted.

2. The combination with a metal mold comprising a pair of movable separable sections, said sections together forming the entire mold cavity, including the bottom, of a pair of parallel spaced rails on which both of said sections are slidably supported at their edges.

3. The combination with a metal mold

comprising a pair of separable sections, said sections together forming the entire mold cavity, including the bottom, of a pair of spaced rails on which said sections are slidably supported, and from which they may be freely lifted each rail having a flat bearing surface, and an upstanding guide-flange at the outer side of such surface.

4. The combination with a metal mold comprising a pair of separable sections, said sections together forming the entire mold cavity, including the bottom, of a pair of spaced rails on which said sections are slidably supported, each rail having a flat bearing surface, and an upstanding guide-flange at the outer side of such surface, said guide-flange being cut away down to the level of the bearing surface at the point where said sections come together.

5. In combination, a metal mold for forming cylindrical articles, comprising a pair of movable separable sections each having an inner surface forming part of the curved wall of the mold cavity, and a pair of plates secured one to each of said sections and serving, when said sections are assembled to form the bottom of the mold cavity, and a pair of spaced rails on which both of said sections are slidably supported, said plates lying between said rails.

6. The combination with a molding machine comprising a frame and a pair of separable mold sections mounted thereon, each containing complementary parts of the mold cavity, said cavity being open at the top, of a plurality of core members adapted to fit within said cavity, and a supporting rack carried by the base to receive the core members when they are removed from the mold cavity, said rack comprising a pair of inclined pans or trays arranged one above the other.

7. The combination with a molding machine comprising a frame and a pair of separable mold sections mounted thereon, each containing complementary parts of the mold cavity, said cavity being open at the top, of a plurality of core members adapted to fit within said cavity, and a supporting rack carried by the base to receive the core members when they are removed from the mold cavity, said rack comprising a pan or tray lined with a sheet of relatively soft metal, whereby damage to the core members by contact with such pan is prevented.

In testimony whereof we affix our signatures.

ROBERT J. OWEN.
HARRY D. RINDSBERG.
